UNITED STATES PATENT OFFICE.

CHARLES MANLIUS HOFFMAN, OF LEBANON, NEW HAMPSHIRE, ASSIGNOR
OF ONE-HALF TO ISAAC N. PERLEY.

POLE OR THILL COUPLING.

SPECIFICATION forming part of Letters Patent No. 595,019, dated December 7, 1897.

Application filed August 26, 1897. Serial No. 649,620. (No model.)

To all whom it may concern:

Be it known that I, CHARLES MANLIUS HOFFMAN, a citizen of the United States, residing at Lebanon, in the county of Grafton and State of New Hampshire, have invented certain new and useful Improvements in Interchangeable Pole or Thill Couplings; and I do declare the following to be a full, clear, and exact description of the invention, such as will enable others skilled in the art to which it appertains to make and use the same, reference being had to the accompanying drawings, and to the letters of reference marked thereon, which form a part of this specification.

It is often desirable to exchange the shafts of a vehicle for a pole, and vice versa; and the object of my invention is to do away with the ordinary bolt and nut and to provide a simple and secure coupling which will permit the rapid exchange above mentioned.

The nature of my invention will be described below and pointed out in the claims.

In the drawings, Figure 1 is a side view, partly broken. Fig. 2 is a broken plan view. Fig. 3 is a detail of the draw-bolt. Fig. 4 is a detail of the locking-plate, partly broken. Like letters refer to like parts.

A is a clip, and B are the clip-jaws.

C is a thill-iron having a draw-head D with a circular eye.

E is the draw-bolt. At one end it has an enlarged circular head f with a circular groove a. The other end has transverse square grooves b cut in quite deeply, also two slight seats c, and the purpose of these grooves and seats will appear below.

H is a locking-plate. This has a keyhole-shaped slot d. The outer face of said plate is irregular, but mostly wedge-shaped, so that when the plate is driven downward it locks tighter and tighter in grooves b in the draw-bolt; but when driven upward quickly loosens and releases said bolt when the end opposite the head registers with the circular portion of slot d.

L is a latch pivoted to locking-plate H. On its rim it has a thumb-piece and on its rear

face a knob r, which snaps into the slot of plate H when the latch is closed and prevents the latter from getting loose. The latch when locked also engages with one of the seats c in the draw-bolt, which gives additional stability to the latch, the purpose of which is to prevent the plate H from working upward and releasing the bolt E. To aid the latch, the lower end of plate H increases in thickness and its face inclines outward, nearly corresponding with the upper end of said plate.

The purpose of groove a is to provide an attachment for a cord, which would prevent bolt E from dropping into the dirt when removed. A similar provision can be made for plate H by drilling a hole in its top and inserting a cord.

The operation of the device is as follows: To remove shafts, pull back the latch, drive the plate H up until circular portion of slot d registers with the end of the bolt F, opposite the head f, and then remove plate H and bolt E, when the draw-head can be removed. To attach a pole, insert it in proper place, pass bolt E through until the head f rests tightly against the clip-jaw, insert plate H, and drive it down tight, or until the latch will lock hard under the bolt.

Having fully described my invention, what I claim, and desire to secure by Letters Patent, is—

1. The combination with the clip-jaws and draw-head, of a draw-bolt with transverse grooves at one end, a slotted, wedge-shaped locking-plate engaging with said grooves, and a latch closing over said plate and under the end of said bolt projecting outside of the plate, as set forth.

2. The combination with the clip-jaws and draw-head, of a draw-bolt with transverse grooves at one end, a locking-plate wedge-shaped or partially inclined on its outer face and having a keyhole-shaped slot engaging said grooves in the draw-bolt, and a latch closing over said plate and under the end of said bolt projecting beyond the plate, as set forth.

3. The combination with the clip-jaws and draw-head, of a draw-bolt having at one end an enlarged, grooved head and at the other end transverse grooves, a locking-plate wedge-shaped on its outer face and having a key-hole-shaped slot engaging with said grooves in the draw-bolt, and a latch provided on its rear face with a knob adapted to lock into said

keyhole-shaped slot when the latch is closed, as set forth.

In testimony whereof I affix my signature in presence of two witnesses.

CHARLES MANLIUS HOFFMAN.
